UNITED STATES PATENT OFFICE.

LINN BOYD HARROD, OF LITTLE ROCK, ARKANSAS.

CARBURETER ATTACHMENT.

1,272,483.

Specification of Letters Patent. Patented July 16, 1918.

Application filed December 7, 1917. Serial No. 206,087.

To all whom it may concern:

Be it known that I, LINN B. HARROD, a citizen of the United States, and a resident of Little Rock, in the county of Pulaski and State of Arkansas, have invented certain new and useful Improvements in Carbureter Attachments, of which the following is a specification.

My invention relates to improvements in attachments for carbureters, and it consists in the combinations, constructions, and arrangements herein described and claimed.

My invention relates more particularly to means for heating the air coming through the air intake of a carbureter, thereby facilitating the starting of the engine with which the carbureter is associated.

A further object of my invention is to provide a carbureter attachment for heating the air prior to its admixture with the vaporized fuel in which the air is forced to pass through narrow highly heated passages, thereby insuring the heating of the air quickly and thoroughly.

25 A further object of my invention is to provide a device of the type described, in which the parts may be readily assembled or replaced.

Other objects and advantages will appear 30 in the following specification, and the novel features of the invention will be particularly pointed out in the appended claims.

My invention is illustrated in the accompanying drawings forming a part of this application in which:

Figure 1 is a side view of the device as applied to a carbureter.

Fig. 2 is an enlarged sectional view through the device.

40 Fig. 3 is an end view of the device.

Fig. 4 is a section along the line 4—4 of Fig. 2.

Fig. 5 is a section along the line 5—5 of Fig. 2.

45 Fig. 6 is a section along the line 6—6 of Fig. 2.

Fig. 7 is a section along the line 7—7 of Fig. 2.

50 Fig. 8 is a side view of the core removed from the cylinder, and

Fig. 9 is a diagrammatic view showing the circuit connections.

In carrying out my invention I provide an insulating cylinder 1 which may be made of 55 fiber or any other suitable material. The intake end of the cylinder 1 is provided with

a flanged ring 2 which is secured in position by means of screws 3. A screen 4 is held against the end of the cylinder 1 by means of the ring, as clearly shown in Fig. 2. The 60 opposite end of the cylinder is designed to communicate with the carbureter. In the present instance, I have shown the cylinder 1 as being secured to the air intake pipe 5 of the carbureter, but obviously any suitable 65 connection between the attachment and the carbureter might be made. It is desirable, of course, to have the heating attachment as close to the carbureter as possible.

Disposed within the cylinder 1 and spaced 70 therefrom, is a cylindrical core 6 which is also made of insulating material such as asbestos. Extending inwardly from the ends of the core are insulating bushings 7. A rod 8 extends centrally through the core and 75 through the bushings, this rod being threaded at its ends and being provided with nuts 9.

At one end of the core is a conducting 80 plate 10 which is provided with laterally extending spacing lugs 10^x, see Fig. 4, and which has an integral laterally extending conducting bar 12 disposed in engagement with the outer surface of the core 6. The bar 12, as will be observed from Fig. 2, is 85 provided at intervals with bolts 13 which form means for attaching the heating element, as will be explained later. It will be noted that the bar 12 terminates short of the 90 opposite end of the core 6.

On the exterior of the plate 10 and in electrical contact therewith, is a backing plate 14 having a laterally extending slotted flange 14^y which is bent at right angles and which is held in position by means of a binding screw 15, see Fig. 2. The plate 14 constitutes a supporting member for the end of the core, as well as a means of conducting 95 current to the plate 10 and bar 12.

At the opposite end of the core is a plate 100 16 which, as will be seen from Fig. 7, is provided with spacing lugs 16^x. The plate 16 is provided on one edge with a slotted flange or lug 16^y which is arranged to receive a binding screw 17 for holding the plate in 105 position. It is also provided with a laterally extending conducting bar 18 similar to the bar 12, and provided with bolts 13 for holding the heating element. The plates 10, 14 and 16 have central openings through 110 which the bushings 7 pass, so that when the nuts 9 are tightened, the parts are held

firmly in position while the plates 16 and 10 are insulated from each other. The screws 15 and 17 are provided with nuts 15^a and 17^a, respectively, and with suitable washers 5 for securing the terminals 19 and 20 of the feed wires.

The heating elements are preferably resistance wires of German silver or the like. These resistance wires are arranged in parallel, as shown in Figs. 8 and 9. In these figures, it will be seen that the wires 21 are secured at one end to the binding screw bolts 13, as for instance, those on the bar 18, and then are wound on the core for one and a 15 half turns, being connected to a binding screw of the opposite bar 12. Suitable insulating material in the form of strips 22 is provided for insulating the wires from the bars at portions between the binding screws. 20 Obviously, more or fewer turns may be made without departing from the invention.

From the foregoing description of the various parts of the device, the operation thereof may be readily understood. The air 25 coming through the intake end of the attachment, is strained of particles of dust, lint, and the like, and then is compelled to pass between the inner walls of the tube 1 and the outer surface of the core 6 which is provided 30 with a heating element 22. The latter is heated by current from a battery, generator, or other suitable source, and the air in its passage along the long, narrow space becomes highly heated before entering the carburetor.

The device is simple in construction and the parts are rigidly held together. In this connection, it will be noted that the plate 16 serves not only as a support for the core, but 40 as an electrical conductor for supplying current to the conducting bar 18. It also acts as a spacing member or centering member, since when this plate is in position, the lugs will bring the core exactly in the center of the 45 tube 1. The plate at the opposite end, to wit: the plate 10, serves a similar purpose, as far as the spacing of the core, or rather the centering of the latter is concerned. The binding screws 15 and 17 serve a double purpose, since they serve as means for retaining 50 the core in position, and also as means for effecting the electrical connection. With this form of the device there is very little danger of over-heating. The conducting 55 members are amply large enough to convey the current without danger of fusing, while the core and outer cylinder being made of heat resisting material, are not liable to injury from an excess of current.

60 The inner core may be easily removed by first removing the nut from the end of the rod 8 at the left-hand side of Fig. 2, withdrawing the bushing, releasing the binding screw 15, and withdrawing the plate 14. 65 Now, by releasing the binding screw 17, the

core may be removed as a whole, when the tube 1 has been detached from the carburetor air intake pipe.

I claim:

1. A carburetor attachment comprising an outer tube of heat insulating material, an inner cylindrical heat insulating core, conducting end plates secured to said core and having laterally extending portions parallel to the axis of the core and lying on the surface of the core, resistance wires carried by the core and in electrical connection with said extensions, and means carried by the plates for spacing the core from the tube and for centering it. 70

2. A carburetor attachment comprising an outer tube of heat insulating material, an inner core of heat insulating material, means for spacing the core centrally within the outer tube, electrical heating elements carried by said inner core on the outer surface thereof, and binding posts carried by the tube and arranged to engage conducting extensions of the core for holding the core in position and for effecting electrical connections with the heating elements of the core. 75

25 3. A carburetor attachment comprising an outer tube of heat insulating material, an inner core of heat insulating material, conducting end plates for said core, binding screws carried by the outer tube and secured to said conducting end plates for holding the core in position, conducting strips carried by the core on the outer surface thereof, and resistance wires connected to said conducting strips. 90

4. A carburetor attachment comprising an outer tube of heat insulating material, an inner core of heat insulating material, conducting end plates for said core, binding screws carried by the outer tube and secured to said conducting end plates for holding the core in position, conducting strips carried by the core on the outer surface thereof, resistance wires connected to said conducting strips, and retaining means passing through the center of the core for holding the end plates to the core, said retaining means being insulated from said end plates. 100

5. In a carburetor attachment, an outer cylindrical heat insulating tube, an inner cylindrical heat insulating core, conducting end plates secured to said core, said conducting end plates having spacing lugs for centering the core with respect to the tube, retaining means passing through the center of the core for holding the end plates to the tube, said retaining means being insulated from said end plates, binding posts carried by the outer tube, and electrical connections between the end plates and said binding posts. 110

6. In a carburetor attachment, an outer cylindrical heat insulating tube, an inner cylindrical heat insulating core, conducting 120

- end plates secured to said core, said conducting end plates having spacing lugs for centering the core with respect to the tube, retaining means passing through the center 5 of the core for holding the end plates to the core, said retaining means being insulated from said end plates, binding posts carried by the outer tube, electrical connections between the end plates and said binding posts, 10 conducting strips connected to said end plates, and resistance wires extending between the conducting strips.
7. A carbureter attachment comprising an outer cylindrical heat insulating tube, an inner cylindrical heat insulating core, conducting end plates for said core, said conducting end plates having lugs extending laterally and engaging the inner surface of the tube for centering the core, said end 15 plates having central openings, insulating bushings extending through the central openings in the end plates and into the core, a retaining rod extending through said bushings and being provided with nuts for 20 holding the end plates in place, a conducting strip extending from each end plate along the outer surface of the core, wire securing means carried by said conducting strip, and resistance wires extending from 25 one conducting strip to the other in the space between the core and the tube.
8. A carbureter attachment comprising an outer cylindrical heat insulating tube, an inner cylindrical heat insulating core, conducting end plates for said core, said conducting end plates having lugs extending laterally and engaging the inner surface of the tube for centering the core, said end 30 plates having central openings, insulating bushings extending through the central openings in the end plates and into the core, a retaining rod extending through said bushings and being provided with nuts for 35 holding the end plates in place, a conducting strip extending from each end plate along the outer surface of the core, wire securing means carried by said conducting strip, and resistance wires extending from 40 one conducting strip to the other in the space between the core and the tube.
9. A carbureter attachment comprising an outer cylindrical heat insulating tube, an inner cylindrical heat insulating core, conducting end plates for said core, said conducting end plates having lugs extending laterally and slotted to receive a screw bolt, 55 and screw bolts carried by the tube and arranged to enter said slotted lugs for securing the parts in position and for effecting electrical connection with the respective plates. 60
10. In a carbureter attachment, an outer cylindrical heat insulating tube, an inner cylindrical heat insulating core, conducting end plates secured to said core, said conducting end plates having lugs extending laterally and slotted to receive a screw bolt, 65 and engaging the inner surface of the tube for centering the core, said end plates having central openings, insulating bushings extending through the central openings in the end plates and into the core, a retaining rod extending through said bushings and being provided with nuts for holding the end plates in place, a conducting strip extending from each end plate along the outer 70 surface of the core, wire securing means carried by said conducting strip, resistance wires extending from one conducting strip to the other in the space between the core and the tube, one of said conducting plates having a lug bent laterally and slotted to receive a screw bolt, a backing plate in electrical engagement with the other plate and having a lug bent laterally and slotted to receive a screw bolt, screw bolts carried by the tube and arranged to enter said slotted 75 lugs for securing the parts in position and for effecting electrical connection with the respective plates, and a strainer at the end of said outer tube, and means for securing the strainer in position. 80
11. In a carbureter attachment, an outer cylindrical heat insulating tube, an inner cylindrical heat insulating core, conducting end plates secured to said core, said conducting end plates having spacing lugs for centering the core with respect to the tube, retaining means passing through the center of the core for holding the end plates to the tube, said retaining means being insulated from said end plates, binding posts carried by the outer tube, electrical connections between the end plates and said binding posts, and binding posts carried by the tube for holding the end plates and for conducting current to said end plates. 95

LINN BOYD HARROD.
